(57) **CLAIM**

The ornamental design for a lens cover, as shown and described.

DESCRIPTION

FIG. 1 is a front top perspective view of a lens cover showing my new design.

FIG. 2 is a bottom rear perspective view thereof at a first angle.

FIG. 3 is a bottom rear perspective view thereof at a second angle.

FIG. 4 is a left side elevation view thereof.

FIG. 5 is a right side elevation view thereof.

FIG. 6 is a front elevation view thereof.

FIG. 7 is a rear elevation view thereof.

FIG. 8 is a bottom plan view thereof; and,

FIG. 9 is a top plan view thereof.

No claim is made to the dash-dash lines which form no part of the claimed design. No claim is made to portions which are not shown. No claim is made to the internal materials shown in cross-section lining.

1 Claim, 6 Drawing Sheets
